[57] CLAIM

The ornamental design for a clothing hamper, as shown and described.

DESCRIPTION

FIG. 1 is a front elevational view of a clothing hamper showing my new design;

FIG. 2 is a side elevational view thereof;

FIG. 3 is a rear elevational view thereof;

FIG. 4 is an elevational view of the side opposite that

FIG. 5 is a top plan view thereof;

FIG. 6 is a bottom plan view thereof; and

FIG. 7 is a perspective view thereof.

The lined pattern on the sides, top and bottom of the hamper represents a conventional quilted material. The cross-hatching, which is partially shown for ease of illustration on the parallel strips in FIGS. 1-4, represents a conventional nylon material.
